Primary Examiner — Khawaja Anwar*Assistant Examiner* — Mojtaba Tehrani(74) *Attorney, Agent, or Firm* — BakerHostetler(57) **CLAIM**

The ornamental design for a mobile phone case, as shown and described.

DESCRIPTION

FIG. 1 is a perspective view of a mobile phone case in a particularly open state, showing the claimed design;

FIG. 2 is a top view showing the case in closed state;

FIG. 3 is right view face thereof;

FIG. 4 is a side view thereof;

FIG. 5 is left view thereof;

FIG. 6 is an opposite side view thereof;

FIG. 7 is a bottom view thereof;

FIG. 8 is a front view showing the case in open state;

FIG. 9 is a rear view thereof;

FIG. 10 is a front view thereof; and,

FIG. 11 is a rear view thereof.

The evenly broken lines illustrating the cellular device inside of the case shown in FIGS. 10 and 11 are directed to the unclaimed environment and form no part of the claimed design.

1 Claim, 5 Drawing Sheets(56)
